LINK SUPPORT

Chester C. Sidwell, Pico, Calif.

Application September 4, 1935, Serial No. 39,135

5 Claims.

(Cl. 20—24)

This invention relates to a link support for utilization as a hanger for closures, such as windows, doors, gates and other structures designed for horizontal rectilinear movement.

5 An object of the invention is to provide a hanger of the above character embodying an arrangement of links adapted to permit horizontal rectilinear movement of a structure suspended therefrom in a fashion whereby a balance or 10 equalization of thrusts is maintained throughout the length of the path of travel of the structure and whereby the latter will normally remain at rest in any position throughout the length of its path of travel and without the employment 15 of counter-balances such as weights and springs.

A further object is to provide a construction and arrangement in a device of the above character constituting an improvement in the construction in the mounting for windows, doors 20 and the like set forth in United States Patent Number 2,013,719, bearing issue date of September 10, 1935, in that the employment of intermeshing toothed segments as employed in such patented construction may be dispensed with.

25 Another object is to provide a link hanger which may be employed either to support a single structure or a plurality of structures, such as gates, doors, windows, and other closures and which is adapted to be arranged when employed 30 as a mounting for double closures to effect movement of the closures either in overlapping parallel relation or toward and away from each other on a common plane.

With the foregoing objects in view together 35 with such additional objects and features as may subsequently appear, the invention is carried into effect by the provision of the parts, and of the combination, construction and arrangement of parts set forth in the following detailed description and depicted in the accompanying drawings, 40 showing several embodiments of the invention, by way of example, and in which:

Fig. 1 is a view of the link support showing it 45 as adapted to serve as a hanger for a single structure such as a closure and depicting it in its closed or folded position:

Fig. 2 is a view of the device shown in Fig. 1 in its open or extended position:

50 Fig. 3 is a view in vertical section taken on the line 3—3 of Fig. 1:

Fig. 4 is a view of the hanger as applied and arranged to afford a structure for a double closure where a pair of closures are designed to be 55 moved toward and away from each other on a

common plane and showing the closure in the open position:

Fig. 5 is a view in elevation of the structure shown in Fig. 4 with the closures disposed in their closed position:

Fig. 6 is a view in elevation showing the invention as applied to a hanger for a pair of closures arranged to be moved in parallel overlying relation to each other and showing the closures in their closed position:

Fig. 7 is a view of the structure shown in Fig. 6 with the closures arranged in their open position:

Fig. 8 is a plan view of the structure shown in Fig. 6.

Referring to the drawings more specifically A indicates generally a horizontally extending supporting member which may be of any suitable construction and which is designed to be disposed in an elevated position and carried on any suitable supporting structure as occasion may require and not necessary to be here shown.

Pivots mounted on the supporting member A and spaced longitudinally thereon is a pair of upwardly extending links 10 and 11 secured to the supporting member A by pivots 12 and 13 to rock to and from a vertically extended position; the links 10 and 11 being pivotally connected at their upper ends to a horizontal tie bar 14 by pivots 15 and 16 to move collectively. The distance between the pivots 12 and 13 corresponds to the distance between the pivots 15 and 16 and likewise the distance between the pivots corresponds to the distance between the pivots 13 and 16 whereby on rocking the links 10 and 11 they will be maintained in parallel relation to each other in any position they may assume and whereby the tie bar 14 will be maintained horizontal and parallel with the plane of the pivots 12 and 13.

A pair of links 17 and 18 are connected at their upper ends by pivots 19 and 20 to the links 10 and 11 adjacent to but spaced from the upper or outer ends thereof but with the axes of the pivots 19 and 20 spaced equi-distant between the pivots 12 and 15 and 13 and 16 respectively, and with the axis of the pivot 19 disposed on a plane extending through the plane of the axis of the pivots 12 and 15 and with the axis of the pivot 20 disposed on a plane extending through the axis of the pivots 13 and 16. The links 17 and 18 extend downwardly from their pivots 19 and 20 and are designed when the links 10 and 11 are extended vertically to be disposed parallel therewith, as particularly shown in Fig. 1.

The lower ends of the links 17 and 18 are connected by pivots 21 and 22 to a horizontal tie B which may comprise a beam or other structure designed to be suspended from the link structure. The distance between the axes of the pivots 21 and 22 correspond to the distance between the axes of the pivots 12 and 13, and the distance between the pivots 19 and 20 and the pivots 23 and 22 correspond to the distance between the pivots 19 and 12, and 20 and 13, respectively so that on swinging movement of the links 17 and 18 the supported tie B will be maintained parallel with the horizontal.

Depending from the tie bar 14 is a hanger 23 and pivotally connected by a pivot 24 to the hanger 23 is a thrust link 25 which is connected at its outer end by a pivot 26 to the link 17 at a point on the latter spaced a distance from the axes of pivot 19 corresponding to the distance between the pivots 19 and 15. The axes of the pivot 24 is disposed on a plane below the axes of the pivots 19 and 20 and at a point on a plane extending mid-way between the axes of the pivots 15 and 16. While the link 25 is shown in Figs. 1 and 2 as connecting with the link 11, it manifestly may be connected to the link 18 in a similar fashion, as shown in Fig. 4.

In the operation of the form of the invention just described, assuming the parts to be disposed in the position shown in Fig. 1, a longitudinal pull on the supported member on tie B in a direction opposite the direction of projection of the link 25 from the hanger 23, the links 17 and 18 will swing on their pivots 19 and 20 in corresponding directions and at the same time a longitudinal thrust will be imposed on the link 25 and transmitted through the hanger 23 to the tie bar 14 to effect longitudinal movement of the latter which movement effects swinging of the links 10 and 11 in parallel relation to each other in a direction of incline opposite that of the links 17 and 18.

By arranging the several links and spacing the pivotal connection as shown and described, longitudinal movement of the supported member B will be rectilinear. In this fashion the parts will move from the position shown in Fig. 1 to the position shown in Fig. 2, or to any intermediate position, and in whatever position the parts may assume a balance or equalization of thrusts will be established whereby the suspended member B will be maintained in any position it may assume without any tendency to move from such position in either direction.

In the arrangement shown in Figs. 4 and 5 a pair of the link support assemblies C and D corresponding to the construction shown in Figs. 1 and 2 are employed being spaced apart on a supporting element A and being arranged so that swinging movement of one of the supporting members in one direction will effect corresponding movement of the other link support and in opposite direction whereby suspended members B carried thereby will move toward and away from each other on a corresponding plane. For this purpose the thrust link 25 in the assembly C connects with the link 17 and in the assembly D is connected to the link 18.

Interposed between the pair of link support assemblies C and D is a rocker bar 27 pivoted intermediate its ends on a pivot 28 and connecting by pivots 29 and 30 to the ends of links 31 and 32 pivotally connected at their outer ends by pivots 33 and 34 to the links 11 and 10 respectively of the pair of link support assemblies. The pivots 29 and 30 are spaced equi-distant from the axes

28 and the pivots 29 and 33 are spaced apart a distance corresponding to the distance between the pivots 30 and 34, while the pivots 33 and 13 are spaced a distance corresponding to the distance between the pivots 34 and 12.

In the operation of the structure shown in Figs. 4 and 5 movement of either of the supported members B toward and away from its companion supported member will act through the link assembly C or D supporting same, to effect vertical swinging movement of the links 10 and 11 of the assembly as before described, thus effecting longitudinal movement of the link 31 or 32 and thereby actuating the rocker bar 27 to effect longitudinal movement of the other link 31 or 32 which will swing the link 10 and 11 of the other link assembly C or D, and thereby cause longitudinal movement of the other supported member B in a direction opposite that of the supported member B to which movement was initially imparted.

In the arrangement shown in Figs. 6, 7 and 8 pairs of upwardly extending links 40 and 41 are pivotally mounted between a pair of supporting members E and F in longitudinally spaced relation thereon, being secured to the supporting member by pivots 42 and 43 to rock to and from a vertical position. The links 40 and 41 are pivotally connected at their upper ends to a horizontal tie bar 44 by pivots 45 and 46. A pair of links 47 and 48 are connected at their upper ends by pivots 49 and 50 to the links 40 and 41 adjacent to but spaced from the upper or outer ends thereof. The lower ends of the links 47 and 48 are connected by pivots 51 and 52 to a horizontal tie G constituting a portion of a closure or other structure suspended from the link structure.

Depending from the tie bar 44 is a hanger 53 connected by a pivot 54 to a thrust link 55 which is connected at its outer end by pivot 56 to the link 47.

The structure just described is arranged in the fashion previously described with reference to Figs. 1 and 2; the elements being the same and operating in a corresponding manner. However in this instance added elements are provided so that a single link assembly may be utilized to afford a support for a second closure to move parallel with that of the tie G in overlying relation thereto with a differential speed. To accomplish this a pair of links 60 and 61 are connected by pivots 62 and 63 to the links 40 and 41 to depend from the latter and being here shown as connected to the links 40 and 41 respectively intermediate the pivots 42 and 49, and 43 and 50. The lower ends of the links 60 and 61 are connected by pivots 64 and 65 to a tie H forming part of the second closure supported by the link assembly. Projecting upwardly from the tie H is a standard 66 which is connected at its upper end by pivots 67 to a thrust link 68 the outer end of which is connected at the pivot 50 to the link 41.

In the operation in the form of the invention just described, assuming the parts to be disposed in the position shown in Fig. 6, on moving the supported member or tie G to the left the links 47 and 48 will advance and impose an upward thrust on the links 40 and 41 and at the same time will exert a pull on the link 55 so as to swing the links 40 and 41 toward the vertical on their pivots 42 and 43; continued movement of the tie G carrying the links 40 and 41 past the vertical to the oppositely inclined position shown in Fig. 7. During movement of the links 40 and 41 the links 60, 61 and 68 are caused to carry the tie H.

on a path of travel parallel with the tie G but at a slower rate of movement than that of the latter.

An important feature of the invention resides in the fact that by reason of the provision of the drag link 25 or 55 affording a connection between the tie 14 or 44 with the short links 17 or 18, or 47, downward pull on the links 10 and 11 or 40 and 41 when the latter are inclined from the vertical tending to cause the links to move to a horizontal position is neutralized by thrust directed through the tie 14 or 44 and the thrust link such as to counteract the load on the links 10 and 11 or 40 and 41, thereby accomplishing a balance whereby the supported structure will remain at rest at any position in the limit of the path of travel permitted by the link assembly. This balance is effected throughout the length of travel of the supported structure and accordingly the amount of work required to move the structure in either direction within its limit of travel will be the same and there will be no tendency for the supported structure to run free under momentum thus reducing to a minimum any possibility of the supported structure slamming against any stop that may be provided therefor after it has been freed from shifting pressure imposed thereon.

By thus mounting the supported structure its movement will be silent and will be characterized by a gliding motion and which movement may be effected without the aid of any track or guide other than the guiding action afforded by the link assemblage.

Manifestly the supported structure may be of any suitable construction and may comprise a gate, door or window of any desired fabrication, and obviously may embrace anything designed to be suspended and shifted on a rectilinear horizontal path of travel.

I claim:

1. In a link support, a supporting member, a pair of upwardly extending links pivoted on said supporting member, a tie bar connecting the upper ends of said links, a pair of downwardly extending links carried on said pair of upwardly extending links and leading therefrom below said tie-bar, a tie connecting the lower ends of said downwardly extending links adapted to carry a structure to be movably supported, and a link connection between said tie bar and one of said downwardly extending links for equalizing thrusts imposed on said links by the load of the supported structure.

2. In a link support, a supporting member, a pair of upwardly extending links pivoted on said supporting member, a tie bar connecting the upper ends of said links, a pair of downwardly extending links carried on said pair of upwardly

extending links and leading therefrom below said tie-bar, a tie connecting the lower ends of said downwardly extending links adapted to carry a structure to be movably supported, a depending bracket on said tie bar and a thrust link extending between said bracket and one of said downwardly extending links.

3. In a link support, a supporting member, a pair of upwardly extending links pivoted on said supporting member, a tie bar connecting the upper ends of said links, a pair of downwardly extending links carried on said pair of upwardly extending links, a tie connecting the lower ends of said downwardly extending links adapted to carry a structure to be movably supported, a depending bracket on said tie bar and a thrust link extending between said bracket and one of said downwardly extending links, a second pair of downwardly extending links on said upwardly extending links, a tie bar connected to said second pair of links adapted to carry a structure to be moved horizontally, an upwardly extending bracket on said second tie bar, and a thrust link extending between said extension and one of said upwardly extending links.

4. In a link support, a supporting member, a pair of link assemblies each of which embodies a pair of upwardly extending links pivoted on said supporting member, a tie bar connecting the upper ends of said pair of links, a pair of downwardly extending links carried on said upwardly extending links, a tie connecting the lower ends of said downwardly extending links adapted to carry a structure to be movably supported; a rocker bar interposed between said pair of link assemblies, and links connecting the ends of said rocker bar to one of the upwardly extending links of each pair of links.

5. In a support of the character described, a pair of upwardly extending links, means pivotally supporting said links at their lower ends, a tie bar interconnecting the upper ends of said links maintaining said links in uniformly spaced parallel relation to each other, a depending link pivotally connected to the upper portion of each of said upwardly extending links, a tie connecting the lower ends of said depending links maintaining the latter in spaced parallel relation to each other and affording a means of connection to said depending links of a structure to be supported in a suspended position thereby, a downward extension in said tie bar, and a thrust link pivoted on said extension on a plane mediate the pivotal connection of said tie bar with said upwardly extending links, said tie bar having its other end pivotally connected to one of said depending links intermediate the ends thereof.

CHESTER C. SIDWELL.
